UNITED STATES PATENT OFFICE.

EVA KELLER, OF PASADENA, CALIFORNIA.

VOICE PLACER.

Application filed October 27, 1925. Serial No. 65,119.

My invention is what I term a voice placer to be utilized in teaching the proper method of singing, in so-called placing and controlling the voice.

5 An object of my invention is to enable the singer or person to listen to their own voice and judge the proper placement, tone quality of the voice etc. When a person is singing, particularly those who are not accomplished vocalists, it is difficult to properly hear their own voice as the sound developed in the mouth is conducted by the eustachian tubes to the ears and the general vibration is internally conducted to the ears so that they 10

15 do not hear their own voice properly by the external ear, and are therefore unable to judge if it is being properly produced.

One of the objects necessary to attain in proper singing is what is termed a frontal 20 placement of the sound, that is the sound appears to be developed or produced immediately behind the teeth and appears to resound in the nasal chambers. When a voice is so placed it does not have the so-called 25 "throaty" quality.

Another feature necessary in singing is to maintain what is called a "flat mouth", that is, the tongue is held in a flat position against the lower portion of the mouth, 30 forming a large mouth passage and giving what is termed an "open throat".

In my invention of a voice placer I utilize a plate preferably somewhat dished, the lower edge of which is lightly pressed against 35 the teeth. This plate is held in front of the face closely adjacent the end of the nose and appears to resound to the frontal vibrations of a properly placed so-called frontal voice. It is possible that the teeth communicate a 40 certain vibration to the plate and these vibrations are reflected back through the bony structure of the face and the nasal chambers and partially detected through the inner and outer ears. By the use of this resonance or 45 reacting plate a singer is enabled to detect if the voice is properly placed in a so-called frontal position.

Another feature of my invention is a back 50 reflector formed of a dished shape reflecting plate adapted to be held at a slight distance from the mouth and below the mouth to receive the full vibrations of sound of the singing. This reflector throws the sound waves back to the outer ear where they are 55 heard in a natural manner. Thus the singer is able to judge by listening to their own

voice through the outer ear both its proper placement and tone quality.

I prefer to mount both the teeth engaging plate and the distant reflector on one supporting device so that they may both be used at the same time and be properly positioned relative to the mouth. 60

Another feature of my invention comprises a spoon-like device which may be 65 thrust into the mouth to hold the tongue down and pressed into a flat position, this spoon being preferably used with the voice placer device and may be readily disconnected therefrom as practicing singing with 70 the spoon compressing the tongue cannot be carried on for a long period.

My invention will be more readily understood from the following description and drawings, in which; 75

Fig. 1 is a perspective view of my voice placer, illustrating the position and approximate size in reference to a singer. This shows the teeth engaging the front sound plate, the rear sound reflector being below 80 the mouth and the removable spoon engaging the tongue. The singer would preferably hold the voice placer in the hand utilizing the fingers to control the spoon.

Fig. 2 is a plan of the voice placer with the 85 tongue spoon.

Fig. 3 is a vertical longitudinal section on the line 3—3 of Fig. 2.

Fig. 4 is a front elevation taken in the direction of the arrow 4 of Fig. 3. 90

Fig. 5 is a rear perspective view of a modified form of voice placer in which both the reflecting plates are adjustably mounted on a frame.

Fig. 6 is a front perspective view of the 95 voice placer of Fig. 5.

Referring first to the construction shown in Figs. 1, 2 and 3, the voice placer is formed with a front reacting or resonance plate 1, a rear reflecting plate 2, with side bars 3 and 100 4 connecting the plates. These plates are preferably dished as shown in Fig. 3 with the mid section 5 of the plate 1 below the periphery 6 and with the mid section 7 of the plate 2 a greater distance below the periphery 8. The plates are of a somewhat oval shape in front or rear elevation as shown in Fig. 4.

The front plate is preferably inclined 105 backwardly at a more acute angle than the back plate. This is for the purpose of allowing the upper teeth to be placed substan-

tially on the dotted line 9 adjacent the lower edge 10 of the front plate, the plate then being slightly spaced from the nose when the head is properly positioned to direct the voice horizontally.

The forward end 11 of the side bars at the forward curved portion 12 may extend slightly forwardly of the lower edge of the plate and may be spaced wide enough apart 10 to barely touch the face or upper lip; this giving an additional guide to the proper positioning of the plate.

The rear plate is provided with a slot 13 slightly above its lower edge 14 in which is 15 supported the stem section 15 of a tongue spoon 16, this spoon having an enlarged end 17 to engage the tongue. The slot is of sufficient size to allow the enlarged end 17 to have a slight vertical swivelling motion.

20 The manner of using my voice placer as above described is to position the lower edges of the front upper teeth against the front plate 1 on substantially the line 9, the head being positioned to throw the voice substantially horizontally or slightly above the horizontal. The back plate 2 is positioned so that the lower edge 14 is below the mouth; thus the sound waves coming from the mouth impinge directly on this plate.

30 When the singer is singing in the proper manner in the so-called frontal placement of the voice, the front reacting or resonance plate 1 appears to vibrate in accordance with the vibrations of the teeth and also by the 35 sound waves directly impinging thereon reflects or reverts these sound waves or vibrations back through the teeth and through the bony structure of the face. The tones also appear to vibrate in the nasal chambers.

40 These vibrations or tones are readily detected by the singer who thus can ascertain if the voice is properly placed. The front plate 1 also reflects a certain amount of sound to the external ears. The rear plate 2 is relied 45 upon principally for reflecting the sound waves from the mouth back to the outer ears and having its lower edge positioned below the mouth, the full sound waves impinge thereon and some are reflected backwardly.

50 My voice placer is preferably made of material having bars 3 and 4 which may be bent to adjust the plates in proper relative position to the singer.

55 The spoon engaging the tongue is adjusted in position by the fingers, either by pressing downwardly on the portion of the stem in front of the back plate or by levering upwardly on the end of the stem at the rear of the back plate. The singer is thus enabled 60 to hold the tongue in proper position while practicing. As above mentioned the tongue spoon may be readily disconnected from the voice placer and either device used separately.

In the construction of Figs. 4 and 5, a rigid frame 20 having side bars 21 and 22 with a rear bar 23 forms a support for the voice placing reflector plates. These plates designated as the front plate 24 and the rear 70 plate 25 are shaped somewhat as shown in Figs. 1 to 4, but are mounted on cross rails 26 and 27 which have clips or eyes 28 engaging the bars 21 and 22 and allowing their relative sliding movement. The clips or eyes 75 28 are preferably provided with a spring 29 to form sufficient resistance to the sliding motion to hold the clips in proper position.

With the construction of these Figs. 4 and 5 both reflecting plates can be used at the 80 same time or else the front plate may be removed off the free ends of the frame and the voice plate only be used or the voice plate may be removed and the front teeth plate utilized alone.

85 A tongue spoon 29 of substantially the same character as shown in Figs. 1 to 4 is slidably and adjustably mounted in a slot 30 at the rear plate 25. With this construction the free ends 31 of the bars 20 and 21 90 may be pressed lightly against the cheeks and thus enable the singer to determine the proper position of the whole device.

95 It will be seen by the above construction that I have invented a very simple device to enable the vocal student to determine if the voice is properly placed in the mouth and to listen in the proper manner to his own singing. The practicing may be conducted in a soft voice without a strain and thereby enable the singer to acquire proper control without developing incorrect manners of singing, which once acquired are very difficult to overcome.

100 My invention although of a simple design may be considerably changed to suit particular requirements or to illustrate different phases of vocal teaching and may be altered in general construction and in details without departing from the spirit of 105 my invention as indicated in the description, drawings and claims.

110 The sound reflecting plates of the constructions of Figs. 1 to 4 or Figs. 5 and 6 are both relatively adjustable. In Figs. 1 115 to 4 the side bars 3 and 4 would preferably be made of a bendable material and may have a sharper bend than shown in the drawings to position the plates closer together or a flatter curve to space them further apart. Moreover, the angular position of the plates is adjustable in regard to each other by bending the plates at different angles in reference to the supporting bars.

120 The voice placer will be made of suitable material to remain in the position in which the plates are bent.

125 In Figs. 5 and 6 the relative spacing of the plates is secured by moving on the side bars but they are adjusted angularly in re-

gard to each other by slightly bending the material of the plates adjacent their lower edges.

It is thus obvious by the construction shown that my voice placer may be made of an integral and same material by being formed of metal plates as in the construction of Figs. 1 to 4, of a compressed rubber material or other substances which will form good sound reflecting mediums and retain the shape in which they are bent.

In the construction of Figs. 5 and 6 the sound reflecting plates may be made of material entirely different from that of the frame.

In summing up my invention it may be stated that accomplished singers can readily detect when they are placing their voice with the proper so-called frontal placement as they can detect a distinct sound vibration in the forward part of the mouth appearing to be adjacent the upper teeth and also in the nasal passages. With a person who is not so accomplished, my voice placer is of material benefit. The reacting and resonance plate 1 in being placed against the upper teeth distinctly emphasizes any vibration in the front part of the mouth and forcibly brings this to the attention of the pupil. If a person is not placing the voice properly, they do not get this effect and thus can readily detect when the voice is properly placed. This resonance or reacting plate properly re-transmits vibrations back through the teeth, the bony structure of the head and into the nasal passages, emphasizing the effect of frontal placement of the voice. The rear reflecting plate 2 catches the sound waves directly from the mouth and reflects these back to the head where they may be detected by the external ear; thus also allowing the singer to more accurately change the tone of singing.

Having described my invention, what I claim is:

1. A voice placer comprising in combination a frame, a front sound reacting plate adapted to touch the front teeth near its lower edge, and a rear reflecting plate positioned to receive the sound waves from the mouth.

2. A voice placer as claimed in claim 1, in which the frame comprises side bars with an open space therebetween.

3. A voice placer as claimed in claim 1, having in addition a spoon-like device adapted to press the tongue and means for operatively engaging the spoon-like device and one of the plates.

4. A voice placer comprising in combination a dished front reacting plate of substantially oval curvature, a frame connected to said plate, a rear reflecting plate having a dished surface and a substantially oval

contour, said plates being positioned at an angle relative to each other, the front plate being adapted to touch the upper teeth and the lower plate to be in the path of sound waves from the mouth.

5. A voice placer as claimed in claim 4, in which the distance between the plates is adjustable.

6. A voice placer as claimed in claim 4, in which the angular position of one plate relative to the other is adjustable.

7. A voice placer as claimed in claim 4, having in addition a slot through the lower portion of the rear plate and a spoon-like device having a stem extending therethrough, said device being adapted to press the tongue downwardly.

8. A voice placer comprising in combination a pair of side bars with an open space therebetween, a front sound reacting plate operatively connected adjacent one end of the side bars, a rear reflecting plate operatively connected adjacent the rear ends of the said bars, the front plate having its lower edge positioned and adapted to be engaged by the upper front teeth and the rear plate having its lower edge positioned below the direct path of sound waves proceeding from the mouth.

9. A voice placer as claimed in claim 8, in which the front plate is inclined relative to the frame to position said plate slightly spaced from a person's nose and the rear plate is positioned substantially vertically when the voice placer is held to reflect horizontally projected sound waves on its lower edge.

10. A voice placer as claimed in claim 8, in which the side bars are formed of a bendable material, said material being adapted to retain the shape in which it is bent.

11. In a voice placer, a sound reacting plate of substantially oval contour, dished in the center and having a substantially straight lower edge, said plate being adapted to engage the lower edge of the upper front teeth adjacent its lower edge, and means to support said plate.

12. In a voice placer, a sound reflecting plate of substantially oval contour, having a dished center portion, said plate having a forwardly curved lower edge, and means to support said plate with the lower edge below the line of sound waves projecting directly from a person's mouth.

13. In a voice placer as claimed in claim 12, in which the plate is provided with a slot adjacent its lower edge and a spoon-like tongue engaging device slidably mounted in said slot.

In testimony whereof I have signed my name to this specification.

EVA KELLER.
